FABRIC WITH RUBBER INLAY AND EMBROIDERY PATTERNS AND METHOD OF KNITTING SAME

James L. Getaz, Maryville, Tenn.

Application January 30, 1936, Serial No. 61,612

18 Claims. (Cl. 66—172)

This invention relates to knitted fabrics and more particularly to knitted hosiery fabrics and it is an object of this invention to provide an improved fabric of the type described in which 5 there is incorporated during the knitting thereof an additional thread of rubber or elastic which tends to contract the fabric and serves as a garter and in which there is also incorporated yarns to form genuine or mock wrap embroidery patterns 10 on the fabric. It is also an object of this invention to provide a method of forming the fabric.

In the drawings—

Fig. 1 is a plan view of a portion of a fabric constructed in accordance with this invention, 15 the fabric being expanded, and showing the relations of the various threads of which the fabric is formed;

Fig. 2 is a view of the portion of fabric shown in Fig. 1, showing the relations of the wales which appear at the face of the fabric when the fabric 20 is contracted by the rubber or elastic thread; and

Fig. 3 is a diagrammatic view, drawn to a smaller scale, of fabric constructed in accordance with this invention forming a stocking top.

In the drawings there is shown a fabric constructed in accordance with this invention and designed for use as a stocking top. In the making of this fabric on a circular knitting machine the main or body yarn or yarns are knit on the 25 cylinder needles to form a plain fabric and during the knitting of the plain fabric a rubber or elastic thread is fed during a number of the courses, the rubber thread being fed in front of and below the latches of alternate or recurrent needles 30 which are raised in advance of the usual knitting wave in order that when the remaining or intermediate needles are raised during the usual knitting wave these needles will be raised in front of the rubber or elastic thread. Upon selected 35 ones of the needles which are raised in order that the rubber thread may be placed in front and below the latches thereof, embroidery or wrap yarns are placed. In the drawings each of these yarns is shown as being fed to wrap but a single needle in each course and as being fed to different needles in successive groups of courses 40 although a larger number of needles may be wrapped by each embroidery yarn in each course and each embroidery yarn may be fed to the same 45 needle or needles throughout or to different needles in successive courses.

In Figure 1 of the drawings there is shown, in expanded condition, a number of courses, as courses *a* to *q*, and a number of wales, as wales 50 *1* to *11*, of a fabric in accordance with this inven-

tion. Throughout the portion of the fabric shown the main or body yarn *B* is knitted by every needle in each course and the rubber or elastic thread *R* is fed in each course in front of and below the latches of alternate or recurrent needles, as the needles which knit the wales *1, 3, 5, 7, 9, 11* etc., the rubber thread being cast off with the loops of the body yarn at the usual knitting wave, an operation which causes the rubber thread to be engaged between the sinker 10 and needle loops of the wales *2, 4, 6, 8, 10* etc., the feeding and engagement of the rubber thread being the same as shown in my co-pending application S. N. 53,824, filed December 10, 1935.

On selected ones of the needles in front of 15 which the rubber thread *R* is placed the embroidery yarn *E* is wrapped. As shown in Figure 1, in which a genuine wrap is illustrated, the embroidery yarn is wrapped upon the same needle, the needle of wale *9*, for two successive courses, 20 as courses *b* and *c*, and then in the following course *d* wrapped upon an adjacent needle in front of which the rubber thread is placed at either side of the needle previously taking the wrap yarn, as the needle of wale *1*. This gives 25 an embroidery stripe having two stitches of the embroidery yarn in a wale and then two stitches of the embroidery yarn in a wale spaced from the previous embroidered wale by an intervening wale. As described in my prior co-pending application, above mentioned, a fabric having rubber laid in in the manner described is, when contracted, substantially a flat fabric in which the 30 wales knit by the needles in front of which the rubber thread is laid are forced to the face of the fabric while the wales knit by the intervening needles in back of which the rubber thread is floated are forced to the back of the fabric. This results, as shown in Figure 2, in providing 35 a flat fabric in which the embroidered wales lie adjacent to each other when the fabric is in the contracted condition and gives the appearance of a continuous embroidery pattern on a rib fabric although the embroidery stitches are separated by an intervening wale and are spaced apart 40 when the fabric is in an expanded condition. As the fabric is expanded to some extent as knit, the floats of the embroidery yarn are of sufficient 45 length to permit expansion of the fabric.

Where the genuine wrap is used for forming 50 the embroidery pattern it is necessary, owing to the manner in which the wrap threads are fed to the needles, to lay in the rubber thread in each course if it is desired to maintain the rubber thread as a continuous thread as otherwise the 55

floats of the rubber and wrap threads entangle. Where the embroidery thread is fed at the throat plate to form a mock wrap embroidery pattern the rubber thread may be fed to spaced courses only, if desired, and still kept a continuous 5 thread without entangling with the floats of the embroidery thread provided the embroidery thread is taken by needles at a number of places about the needle circle to knit what is known 10 as an "all over" pattern as the short floats of the embroidery yarn then lie close to the fabric and do not cause loops of objectionable size to be formed of the rubber thread float. Where a 15 mock wrap pattern is formed at spaced points, as at opposite sides of the stocking, it is necessary to feed the rubber thread in each course in which the embroidery thread is fed to the needles; but, if the rubber thread is fed in each 20 course it is not necessary to feed the embroidery 25 thread in each course. Where the embroidery thread is fed to form a mock wrap the rubber thread will be placed in front of alternate needles and the embroidery threads will be taken by selected ones of such alternate needles as when the embroidery thread is fed to form a genuine wrap pattern.

What is claimed is:—

1. A plain fabric portion comprising main or body yarn or yarns knit at every wale in a plurality of courses, an elastic thread engaged with said fabric at recurrent wales in a plurality of courses and embroidery yarns knit at recurrent wales in a plurality of courses.

2. A plain fabric portion comprising main or body yarn or yarns knit at every wale in a plurality of courses, an elastic thread engaged with the fabric at recurrent wales in a plurality of successive courses and embroidery yarns knit at a plurality of wales in a plurality of courses.

3. A plain fabric portion comprising main or body yarn or yarns knit at every wale in a plurality of courses, an elastic thread engaged with the fabric at alternate wales in recurrent courses, said rubber thread upon contraction forcing the 45 intermediate wales to the face of the fabric and embroidery yarns knit at a plurality of said intermediate wales in a plurality of courses.

4. A plain fabric portion comprising main or body yarn or yarns knit at every wale in a plurality of courses, an elastic thread engaged with the fabric at alternate wales in successive courses for a plurality of courses, said rubber thread upon contracting forcing the intermediate wales to the face of the fabric and an embroidery yarn knit at 50 a single intermediate wale in each of a plurality of courses.

5. A plain fabric portion comprising main or body yarn or yarns knit at every wale in a plurality of courses, an elastic thread engaged with the fabric at alternate wales in successive courses, said rubber thread upon contracting forcing the intermediate wales to the face of the fabric and an embroidery yarn knit at adjacent intermediate wales in successive groups of courses.

6. A plain fabric portion comprising main or body yarn or yarns knit at every wale in a plurality of courses, an elastic thread engaged with the fabric at alternate wales in recurrent courses and embroidery yarns knit at a plurality of intermediate wales, said embroidery yarns being on spaced wales when the fabric is expanded and said elastic thread forcing the intermediate wales to the face of the fabric and causing said embroidery 70 yarns to appear as on adjacent wales when the 75 fabric is contracted.

7. A plain fabric portion comprising main or body yarn or yarns knit at every wale in a plurality of courses, an elastic thread engaged with the fabric at alternate wales in recurrent courses and embroidery yarns knit at a plurality of intermediate wales, said elastic thread contracting said fabric with said embroidered wales at the face of the fabric. 5

8. A plain fabric portion comprising main or body yarn or yarns knit at every wale in a plurality of successive courses, an elastic thread engaged with the fabric at alternate wales in recurrent courses and embroidery yarns knit at a plurality of intermediate wales, said elastic thread contracting said fabric with said embroidered wales appearing as adjacent wales at the face of the fabric. 10 15

9. Steps in a method of knitting a fabric comprising knitting a plain fabric of a main or body yarn engaging rubber thread in alternate wales 20 of the fabric and forming loops of embroidery yarns on the loops of the body yarn in selected wales intermediate said alternate wales during the knitting of said fabric.

10. A tubular stocking having a top of weft 25 ground fabric comprising wales and courses, the combination therewith of design threads forming wrap designs on said ground fabric at selected stitches of alternate wales and an elastic thread under tension incorporated unknit in said ground 30 fabric at the rear of said alternate wales, said elastic thread drawing said alternate wales into close proximity with each other, said elastic thread also acting as a garter.

11. A tubular stocking having a top of weft 35 ground fabric comprising wales and courses, the combination therewith of design threads forming wrap designs on said ground fabric at selected 40 stitches of spaced wales and an elastic thread under tension incorporated unknit in said ground fabric at the rear of said spaced wales, said elastic thread drawing said spaced wales into close proximity with each other, said elastic thread also acting as a garter.

12. A tubular fabric knitted of a weft ground 45 thread comprising wales and courses, the combination therewith of design threads forming wrap designs on the ground fabric at selected 50 stitches of selected spaced wales in selected courses and an elastic thread under tension incorporated unknit for one or more courses in said ground fabric, said elastic thread drawing said spaced wales into close proximity with each other.

13. A tubular stocking having a top of weft 55 ground fabric comprising wales and courses knit entirely of a ground thread or threads, the combination therewith of design threads forming knit designs on said ground fabric at selected 60 stitches of selected spaced wales in selected courses and an elastic thread under tension incorporated in the wales of the ground fabric, said elastic thread drawing said spaced wales into close proximity with each other.

14. A tubular stocking having a top of weft 65 ground fabric comprising wales and courses knit entirely of a ground thread or threads, the combination therewith of design threads forming 70 designs knitted on said ground fabric at selected stitches of selected spaced wales in selected courses, the design threads passing to the rear of the fabric as floats between said selected stitches, and an elastic thread under tension incorporated coursewise in the wales of the ground fabric, said elastic thread drawing said 75

spaced wales into close proximity with each other.

15. A tubular stocking having a top of weft ground fabric comprising wales and courses knit entirely of a ground thread or threads, the combination therewith of design threads forming wrap designs on said ground fabric at selected stitches of selected spaced wales in selected courses, and an elastic thread under tension incorporated coursewise in the wales of the ground fabric, said elastic thread drawing said spaced wales into close proximity with each other.

16. A tubular stocking having a top of weft ground fabric comprising wales and courses knit entirely of a ground thread or threads, the combination therewith of design threads forming designs knitted on said ground fabric at selected stitches of spaced apart wales, the design threads passing to the rear of the fabric as floats between said selected stitches and an elastic thread incorporated coursewise in the wales of the ground fabric, said elastic thread passing behind said spaced wales and drawing the same into close proximity with each other.

17. A tubular stocking having a top of weft knitted ground fabric comprising wales and courses, the combination therewith of design threads forming wrap designs on said ground fabric at selected stitches of selected courses in selected nonadjacent wales and an elastic thread under tension incorporated unknit for one or more courses in said ground fabric, said elastic thread drawing the said nonadjacent wales into close proximity with each other to form a unitary 10 pattern effect of the selected wrap stitches on the said nonadjacent wales, the said elastic thread also acting as a garter.

18. A tubular stocking having a top of weft knitted ground fabric comprising wales and 15 courses, the combination therewith of an elastic thread under tension incorporated unknit for one or more courses in said ground fabric, said elastic thread drawing nonadjacent wales into close proximity with each other and wale threads 20 forming wrap designs on said ground fabric at selected stitches of selected courses in selected nonadjacent wales.
